CLAIM

The ornamental design for a display screen or portion
thereof with graphical user interface as shown and
described.

DESCRIPTION

The file of this patent contains at least one drawing/photograph
executed in color. Copies of this patent with color
drawing(s)/photograph(s) will be provided by the Office
upon request and payment of the necessary fee.

The sole FIGURE shows a display screen or portion thereof
with graphical user interface showing our new design.

The peripheral dashed broken lines illustrate a display
screen or portion thereof, and form no part of the claimed
design.
